UNITED STATES PATENT OFFICE.

LOUIS D. CHERRY, OF PHILADELPHIA, PENNSYLVANIA.

TELEPHONE WRITING TABLET.

Application filed August 24, 1927. Serial No. 215,131.

This invention relates to a telephone writing tablet, and more particularly to a tablet adapted for attachment to a desk telephone.

The primary object of this invention is to generally improve and simplify that type of telephone attachment whereby a roll of paper is carried thereby and adapted to be drawn over a support or table provided with means for severing portions of the paper having memorandum or notations thereon.

Furthermore, the invention aims to provide means to prevent the collapsing of the side walls of the support during the attachment of the same to the telephone and to simplify the means of attaching the device to the telephone.

Furthermore, there is provided in the present invention means whereby a pencil may be conveniently associated with the device and furthermore wherein the pieces of torn paper bearing the memorandum or notation may be attached thereto so that certain data will be at hand during an outgoing call.

With the foregoing and other objects in view as the nature of the invention will be better understood, the same comprises the novel form, combination and arrangement of parts hereinafter more fully described, shown in the accompanying drawing and claimed.

In the accompanying drawing forming part of this application and wherein like numerals indicate like parts:

Figure 1 is a fragmentary side elevation of a conventional desk telephone equipped with my improved device.

Figure 2 is a section taken substantially upon the line 2-2 of Figure 1 and looking downwardly in the direction of the arrows for disclosing the attachment in top plan, and

Figure 3 is a bottom plan view of the attachment, the paper roll being removed therefrom.

Now having particular reference to the drawing, A designates the pedestal or stand of a conventional desk telephone with which my device is to be associated. The attachment proper is preferably stamped from a sheet of tin or suitable metal and comprises a flat desk portion 5 having depending flanges 6-6 at opposite edges thereof said flanges being extended beyond the forward end of the desk portion to provide curved

arms 7-7 that are formed at their outer ends with registering openings for receiving a paper roll spindle 8-8 headed at one end and threaded at the opposite end for receiving a binding nut as clearly disclosed in Figures 2 and 3.

The desk portion 5 of the tablet has two pairs of transverse slits or incisions formed therein, said pairs being adjacent the opposite ends of the desk portion, while between each pair of the slots or incisions, the metal is forced upwardly into a plane above the upper surface of the desk portion as at 9-9, thus providing a pair of transversely extending paper channels beneath these upwardly pressed portions through which paper may be inserted. With this end in view there is provided a roll of paper 10 arranged upon the spindle 8 in such a manner as to permit the roll to freely rotate thereon. Obviously the paper intermediate the upwardly pressed portions 9-9 of the desk portion is supported upon the desk portion in order that said paper may be written upon. Obviously by drawing the paper through the channels the same may be torn by drawing the material across the lower edge of the outer end-most channel 9.

The inner flange 6 of the desk portion 5 is formed with a pair of longitudinally spaced openings, the one adjacent the inner end of the desk portion being at a lower plane than the other opening, and through which are to extend the legs of a J bolt 11, the bight portion of which is adapted for engagement around the telephone standard A, while the longer leg of the bolt will extend through an opening at the opposite flange 6 of the desk portion after which a wing nut 12 is threaded thereon outwardly of the flange so that the bolt may be drawn through the flanges for tightly binding the attachment to the phone standard. In order to negative any liability of the inward bending of these flanges 6-6 there is arranged between the legs of the bolt a transversely extending block 13 that engages at its opposite ends the inner surfaces of said flanges 6-6, see Figure 3. Furthermore, it will be noted that the forward longitudinal edge of this block 13 is directly in back of the rear slit or incision of the pair of slits or incisions provided for the formation of the foremost paper guide channel 9 of the flat desk portion 5. The short leg of the J-bolt extends through the inner flange 6 forwardly

of the block and obviously all pressure exerted transversely of the desk portion adjacent said slit or incision by the attachment of the telephone to the tablet will be taken up by the rigid block 13 so that there will be no distortion of the paper guide channel 9 which would otherwise prevent the proper feeding of the paper therethrough.

The outer flange 6 of the desk portion is formed with a depending tongue 14 to which is secured the lower end of a vertically extending pencil supporting tube 15, while also secured thereto is an upwardly and slightly forwardly extending pin 16 provided at its upper end with a turned over hook 17, this pin providing a file for the memorandum slips that are torn from the attachment.

It will therefore be seen that I have provided a highly novel, simple, and efficient and useful telephone writing tablet that is well adapted for all the purposes heretofore designated, even though I have herein shown and described the invention as consisting of certain detail structural elements, it is nevertheless to be understood that minor changes may be made therein without affecting the spirit and scope of the appended claims.

Having thus described the invention, what I claim as new and desire to secure by Letters Patent is:—

The herein described telephone writing table consisting essentially of a flat desk portion, depending longitudinally extend-

ing flanges at the opposite edges of the desk portion, paper roll carrying means at one end of the desk portion, the desk portion being provided adjacent the paper roll carrying end with a pair of spaced transverse incisions, the material between the incisions being forced upwardly into a horizontal plane above the surface of the desk portion to provide a transverse paper guide channel, a block of rigid material interposed between and crowded against and held in position solely by said flanges, the rear edge of said block being disposed directly in front of the foremost incision, the innermost flange having a pair of openings arranged at opposite sides of the block and the outer flange having an opening in rear of the block registering with the corresponding opening of the innermost flange, and a J-bolt having a short leg arranged through the forward opening of the innermost flange and its long leg arranged through the registering openings in the flanges, the bight portion of the bolt arranged in transverse alinement with the block and adapted for engagement with a telephone standard when said standard is arranged against the innermost flange and in alinement with the block, said legs of the bolt at opposite sides of and adjacent to the sides of the block, and a nut threaded upon the end of the long leg projecting through the opening of the outer flange and disposed against the outer side of said flange.

In testimony whereof I affix my signature.
LOUIS D. CHERRY.
